UNITED STATES PATENT OFFICE.

EUGENE C. STACY, OF TIFFIN, OHIO.

LOAD BINDER.

Application filed July 2, 1924. Serial No. 723,776.

To all whom it may concern:

Be it known that I, EUGENE C. STACY, a citizen of the United States, residing at Tiffin, in the county of Seneca and State of Ohio, have invented a new and useful Load Binder, of which the following is a specification.

This invention relates to load binders, one of the objects being to simplify and otherwise improve upon structures of this character so that the cost of production can be materially reduced without reducing the efficiency of the tool.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings—

Figure 1 is a side elevation of the load binder embodying the present improvements.

Fig. 2 is an enlarged plan view of a portion thereof.

Fig. 3 is a view partly in side elevation and partly in section of the structures shown in Fig. 2.

Fig. 4 is a section on line 4—4, Fig. 3.

Referring to the figures by characters of reference 1 and 2 designate opposed longitudinally channelled heads, each of which is provided at one end with an arm 3 which is crooked to provide an angle portion 4. Studs 5 may be extended laterally from the outer sides of the respective arms 3 and when the heads 1 and 2 are placed together with their channelled sides toward each other, the arms 3 of the respective heads will be spaced apart, as shown particularly in Fig. 2 so as to receive between them a link 6 which can be held to the arms by a pivot pin 7. A handle which can be made of a bar 8 of steel is adapted to be fitted snugly within the matching panels in the heads, 1 and 2 and is held therein by rivets

9 extending transversely through the heads and through the bearing. This handle bar 8 can be of any stock size and can be cut to any length desired.

A yoke indicated at 10 is adapted to straddle the fork formed by the spaced arms 3 and has eyes 11 for the reception of the studs 5.

A structure such as has been described is advantageous because the parts thereof can be made cheaply and can be assembled readily. The heads 1 and 2 and their arms 3 can be of high grade metal castings and can be easily placed in engagement with the studs 5. At the same time the heads 1 and 2 can be placed astride the bar 8, which as before stated, can be of stock size. By means of the rivets 9 the parts can all be held properly assembled and as the bar 8 can be cut of any desired length, the complete tool can be constructed readily to meet any reasonable variations in requirements.

As shown particularly in Fig. 1 a hook 11 or other element indicated at 11' can be connected to the link 6 while another hook 12 or the like can be connected to the yoke 10. Thus when the lever is swung into yoke 10 the two hooks 11 and 12 will be drawn toward each other and the point of connection between the link 6 and the lever will be moved past the dead center so that the parts will thus be held in place with the engaged load properly bound or tied.

What is claimed is:

1. A load binder including opposed longitudinally channelled heads, arms extending therefrom and cooperating to provide a fork, laterally extending studs upon the arms, a yoke having eyes for the reception of the studs, a handle bar insertible into and between the channelled heads, and means extending transversely through the heads and bar for holding them assembled and for maintaining the studs within the yoke.

2. A load binder including opposed longitudinally channelled heads, arms extending therefrom and cooperating to provide a fork, said arms providing angle portions, a link pivotally mounted between the angle portions of the arms, studs extending laterally from the arms, a yoke pivotally mounted therein and adapted to straddle the

arms, attaching devices connected to the link and yoke respectively; a handle bar seated between the heads and within the channels, and means extending transversely through the heads and bar for holding them assembled and for maintaining the studs within the yoke.

In testimony that I claim the foregoing as my own, I have hereto affixed my signature in the presence of a witness.

EUGENE C. STACY.

Witness:

W. M. MYERS.
